A. DUDAS.

LIFE BUOY.

APPLICATION FILED FEB. 7, 1921.

Patented Apr. 19, 1921.

FIG. - 1.

FIG. - 2.

FIG. 3.

Inventor

Andrew Dudas

By

Gottlieb G. Polachoff

Attorney

UNITED STATES PATENT OFFICE.

ANDREW DUDAS, OF HOMESTEAD, PENNSYLVANIA.

LIFE-BUOY.

1,375,494.

Specification of Letters Patent. Patented Apr. 19, 1921.

Application filed February 7, 1921. Serial No. 442,929.

To all whom it may concern:

Be it known that I, ANDREW DUDAS, a citizen of Hungary, residing at Homestead, in the county of Allegheny and State of Pennsylvania, have invented certain new and useful Improvements in Life-Buoys, of which the following is a specification.

This invention relates to lifebuoys for use in the event of accident at sea or on water and it has for an object to provide an improved and novel construction of lifebuoy adapted to properly sustain the person using the same, and to keep the latter out of direct contact with the water.

For further comprehension of the invention, and of the objects and advantages thereof, reference will be had to the following description and accompanying drawings, and to the appended claims in which the various novel features of the invention are more particularly set forth.

Figure 1 of the drawings is a vertical sectional view, with parts in elevation, of a lifebuoy constructed according to my invention.

Fig. 2 is a plan view thereof.

Fig. 3 is a vertical elevation showing the lifebuoy in use.

In constructing my improved lifebuoy I provide an annular buoyant member or float 10 which is of approximately inverted bell-shape, the top being flared outwardly as at 11 to provide a considerable lateral distribution of the sustaining or supporting element. This float 10 is preferably constructed of cork and may be formed of a series of sections divided by the radial plates 12 and bound together by the hoops 13 and secured at their upper edges to a reinforcing ring 14. This float 10 is preferably covered both inside and outside with cloth material 15, such as burlap.

Secured to and surrounded by the float 10 is a water proof garment comprising legs 16 and a waist portion 17. Extending between the flaring upper part 11 of the float 10 and the waist portion 17 of the garment is a horizontal partition member 18 which may be secured at its outer edge to the float, 50 and at its inner edge to the bottom of a reinforcing band 19 surrounding the garment waist 17, this inner end being here shown as supported by struts 20 which extend upwardly and inwardly inside the float,

to which their lower ends are secured in any suitable manner.

Extending between and secured to the ring 14 and the top of the band 19 is a frusto-conical cover 21 made of rubber or other water proof material, a compartment 60 or space 22 being left between this cover and the partition 18. This cover 21 is provided with an opening 23 in which is suitably fixed an exteriorly screw-threaded metal neck ring 24 upon which is screwed a cap 65 25. Access to the space 22 may thus be readily had by the user of the device, this space being adapted to contain drink, food or the like, in suitable packages, while the downward and outward inclination of the 70 cover 21 sheds any water that may be washed thereon.

The extreme upper edge of the garment projects somewhat above the band 19 and upon this projecting upper portion is provided a belt 26 which may be held slidably in place by ordinary retaining devices indicated at 27.

To hold the legs 16 of the garment in position a pair of stirrups 30 are provided 80 which engage the feet 16' of the garment and are held against displacement by the straps 31 surrounding the heel. The stirrups 30 are suspended from the float 10, the latter having extending therethrough a 85 pair of eye-bolts 32 to which the stirrup cords 33 are attached, a link 34 connecting the stirrups to one another. To reinforce the float at the points where the bolts pass therethrough a pair of plates 35 and 36 may 90 be sunk into the inner and outer walls of the float.

The use of my improved lifebuoy will be apparent from the above description, the legs and waist of the person using it being 95 inclosed by the water proof garment. The considerable lateral distribution of the sustaining element enables the person to be supported with the upper portion of the body well above the water while food and drink 100 may be carried in the compartment 22 to which access may be had by simply unscrewing the cap 25.

Having thus described my invention what I claim as new and desire to protect by Letters Patent of the United States is as follows:

1. A life-buoy comprising an inverted

bell-shaped annular float, a garment comprising legs and a waist portion surrounded and carried by said float, and bracing means extending between the upper part of the 5 float and the said waist portion.

2. A life-buoy comprising an inverted bell-shaped annular float, a garment comprising legs and a waist portion surrounded and carried by said float, and bracing means 10 extending between the upper part of the float and the said waist portion, said bracing means comprising a water proof partition.

3. A life-buoy comprising an inverted bell-shaped annular float, a garment comprising legs and a waist portion surrounded and carried by said float, and bracing means 15 extending between the upper part of the float and the said waist portion, and a cover member of frusto-conical form extending between the top edge of said float and the 20 said garment.

4. A life-buoy comprising an inverted bell-shaped annular float, a garment comprising legs and a waist portion surrounded and carried by said float, and bracing means 25 extending between the upper part of the float and the said waist portion, and a cover

member of frusto-conical form extending between the top edge of said float and the said garment, said cover member being spaced 30 from the said partition to provide a compartment for the purpose specified.

5. A life-buoy comprising an inverted bell-shaped float, a water-proof garment surrounded and carried by said float, said 35 float being divided circumferentially into a series of sections, radial plates separating said sections, and hoops binding said sections together.

6. A life-buoy comprising an inverted 40 bell-shaped annular float, a garment comprising legs and a waist portion surrounded and carried by said float, a reinforcing band surrounding said waist portion, a horizontal 45 bracing partition extending from the upper portion of said float to the bottom of the said reinforcing band, and a cover member of frusto-conical form extending from the upper edge of said float to the top of said reinforcing band.

In testimony whereof I have affixed my 50 signature.

ANDREW DUDAS.
